DEFROSTING CONTROL IN AN AIR-COOLING SYSTEM

John E. Watkins, Maywood, Ill., assignor to Midwest Engineering & Equipment Co., Chicago, Ill., a corporation of Illinois

Application March 6, 1948, Serial No. 13,442

3 Claims. (Cl. 62—4)

1

The invention relates to refrigerating systems generally, and more particularly to refrigerating systems of the flooded evaporator type.

One object of the invention is to provide in a refrigerating system of the above general character a refrigerant evaporator constructed and related to the other elements of the system in a novel manner which greatly facilitates defrosting.

Another object is to provide an improved waste system for draining off the water released in the defrosting of the evaporator and for preventing the water from freezing in other parts of the system during the defrosting operation.

Still another object is to provide a control system whereby periodic defrosting of the refrigerant evaporator is effected automatically when required by the condition of the system.

A further object is to provide a refrigerant evaporator which is simple in construction, which provides a maximum area of heat exchange surface, and which offers a minimum resistance to the flow of the medium to be cooled, such as air, over the heat exchange surfaces.

Other objects and advantages of the invention will become apparent from the following detailed description of the preferred embodiment illustrated in the accompanying drawings, in which:

Figure 1 is an elevational view partly diagrammatic in character of a refrigerating system embodying the features of the invention.

Fig. 2 is a fragmentary view of a modified form of the system.

Fig. 3 is a sectional view of a control valve of the type employed in the system when automatic controls are provided.

Fig. 4 is a diagrammatic view of the electrical defrosting control system.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

For purposes of illustration the invention has been shown in a refrigerating system of the type in which a subfreezing temperature is maintained in a refrigerating room or chamber 5 by continuously circulating the air in the chamber over the heat exchange surfaces provided by a refrigerant evaporator 6. Such circulation of air

2

is effected, in this instance, by a fan or blower 7 driven by an electric motor M. In the exemplary embodiment, the chamber 5 is enclosed by insulated walls 8, the confines of which are indicated in broken lines in Fig. 1, and the evaporator 6, blower 7 and motor M are enclosed in a compartment 9 closely adjacent the chamber 5 but separated therefrom by insulated walls or partitions 10. As shown in Figs. 1 and 2, the evaporator 6 is mounted with one end projecting through an opening 11 in the wall or partition 10 to admit air from the chamber 5 into the compartment. After passing through the evaporator and being cooled thereby, the air is discharged by the blower 7 into the chamber 5 through an outlet opening 12 in the wall 10.

While a refrigerant evaporator of any suitable character may be used in the system, the evaporator 6 herein shown embodies novel features of construction which provide a heat exchange surface of large area, while offering a minimum of resistance to the flow of air therover. In its preferred form the evaporator 6 comprises an elongated cylindrical sheet metal shell 15 equipped with a plurality of longitudinally extending tubes 16 fixed in suitable tube sheets or heads 17 closing opposite ends of the shell. The tubes 16 may be rolled or welded into the tube sheets and are open at opposite ends to provide passages for the flow of air through the evaporator, the inner surfaces of the tubes defining heat exchange surfaces for transferring the heat from the circulating air to the refrigerant contained in the evaporator.

When the system is in operation, the evaporator 6 is filled with liquid refrigerant, such as ammonia, to a level 20 somewhat below the top of the evaporator and this level is maintained as the refrigerant evaporates by continuous introduction of fresh liquid refrigerant through an inlet conduit 21 opening into the bottom of the evaporator. The liquid refrigerant may be supplied from any suitable source, such as a conventional compressor-condenser unit having a motor driven compressor 22 adapted to receive spent or gaseous refrigerant from the evaporator and to deliver hot compressed gas through a hot gas line 23 to a condenser 24. The hot gases are cooled and liquefied in the condenser 24 and delivered through a conduit 25, float valve FV and conduit 26 to a vertically disposed liquid header 27 which has a horizontally disposed leg 28 to which the evaporator inlet branch conduit 21 is connected. When required, additional evaporators may be connected to receive refrigerant from

the leg 28 through conduits 21' similar to the conduit 21.

The spent refrigerant in gaseous form resulting from the evaporation of the refrigerant is drawn off from the evaporator 6 into a suction header 30 which is connected to the suction side of the compressor 22 by a conduit 31. The suction header 30 is arranged above the evaporator and is connected thereto by a branch conduit 32 opening into the upper end of the evaporator. Preferably, the conduit 32 is extended upwardly a substantial distance into the suction header to prevent the return flow of refrigerant which may condense in the header.

As shown in Fig. 1, the liquid header 27 is connected at its upper end to the suction header 30 to provide for the escape of flash gas formed therein. A conduit 33 connected between the suction header and the valve FV serves to draw off flash gas from the valve and to equalize the pressure in the valve housing. It will be understood, of course, that the suction header 30 may serve a plurality of evaporators similar to the evaporator 6 and similarly connected thereto by conduits 32'. It will also be understood that the compressor system will normally serve a plurality of freezer lines or assemblies which may be similar in all respects to that shown and which are connected to the supply conduit 25 and suction conduit 31 by branch conduits 25' and 31', respectively.

Provision is made for closing off the inlet and outlet conduits from the evaporator 6 so that the evaporator can be removed for repair or replacement when necessary without interfering with the operation of other evaporators in the system. For this purpose valves 34 and 35 are interposed in the inlet and outlet conduits 21 and 32. These valves may be manually operable valves of any suitable type. Preferably unions 36 and 37 are provided in the respective conduits between the evaporator and the associated valves to facilitate disconnection of the evaporator.

In accordance with the invention, provision is made for defrosting the evaporator 6 in a simple and efficient manner and for effectually disposing of the waste water resulting from such defrosting. Defrosting is effected by draining the liquid refrigerant from the evaporator 6 and the liquid header 27 into a refrigerant storage reservoir or sump 40 and introducing hot gas into the evaporator.

In a multiple evaporator system such as that shown, the hot gas may be conveniently obtained from the compressor 22 by way of a hot gas line 41 branching from the conduit 23 between the compressor and the condenser 24 and having a branch or branches 41' extending to other freezer lines or assemblies when such are installed. It will be appreciated, of course, that the blower 7 is stopped during the defrosting operation to interrupt the circulation of air in the chamber 5 and thus avoid unnecessary reduction in the temperature of the chamber.

In order to drain the liquid refrigerant from the system into the sump 40, the flow of refrigerant through the supply conduit 25 is shut off by closure of a valve 42 interposed in that conduit and the exhaust connection between the suction header 30 and compressor 22 is interrupted by closure of a valve 43 interposed in the suction conduit 31. The opening of a normally closed valve 44 in a conduit 45 connecting between the leg 28 of the liquid header and the sump 40 permits the refrigerant to drain into the sump. Trapped gas is released from the

5 sump 40 by way of a vent line 46 connecting with the suction header 30 and having interposed therein a valve 47 which is opened at the start of the defrosting operation. Due to the pressure exerted on the refrigerant by the hot gas introduced into the evaporator 6, draining of the system is effected very quickly.

10 The hot gas in the evaporator quickly melts the frost accumulated in the tubes 16. To handle the water thus produced, the invention provides a waste system which, in conjunction with the novel mounting of the evaporator, effectually prevents spillage of the water on the floor of the chamber 5 and serves to drain the water off to a suitable disposal point outside the chamber. To this end the evaporator 6 is mounted so that the water condensate resulting from the melting of the frost in the tubes 16 is drained to a common point and collected in a waste receptacle 50. To this end the evaporator is supported with its longitudinal axis inclined, as shown in Fig. 1 or, where sufficient head room is available, the evaporator may be vertical, as shown in Fig. 2. In either case, the receptacle 50 is located adjacent the lower end of the evaporator in a position to receive the water draining therefrom.

15 20 25 30 35 While the receptacle 50 may be constructed in the form of an elongated trough adapted to operate with a plurality of evaporators, it is preferred to construct it as a shallow convex basin 51 adapted to serve a single evaporator, as shown. Water collected in the basin is discharged through a drain conduit 52 leading to a disposal point outside the chamber 5.

30 35 40 45 50 As the receptacle 50 and at least a part of the drain conduit 52 are exposed at all times to the low temperatures obtaining in the chamber 5, means is provided for applying heat thereto to prevent refreezing of the collected water while the defrosting operation is in progress. While sufficient heat for that purpose may be obtained by running the hot gas supply conduit 41 in close proximity to the basin and the drain and enclosing those elements with a common insulating sheath, it is preferred to provide the lower portion of the basin and the adjacent portion of the conduit 52 with a gas-tight jacket through which the hot gas used for defrosting may be circulated.

55 60 65 70 75 In the exemplary system, the hot gas line 41 has a branch 55 leading to a manifold or distributor 56 which serves to distribute the hot gas to the jackets 53 of the drain receptacles for the various evaporators in the system. During the defrosting operation, hot gas from the header 56 is introduced into the lower end of the jacket 53 by way of a conduit 57 and after passing through the jacket is directed through a conduit 58 to the upper end of the associated evaporator 6. A manually operable valve 59 is provided in the conduit 58 so that it may be shut off when the evaporator is to be disconnected from the system for repair or replacement.

Delivery of hot gas to the jacket 53 and evaporator 6 is controlled by a valve 60 interposed between the hot gas line 41 and its branch 55. This valve is normally closed and is opened only at the beginning of the defrosting operation. It will be evident that with the above arrangement the waste disposal system is automatically heated whenever hot gas is introduced to the evaporator 6 for defrosting the same. Due to the location of the waste receptacle 50 relative to the evaporator all water resulting from the melting of the

frost is collected and conducted from the chamber 5, thus avoiding accumulation of ice in the chamber and making unnecessary periodic defrosting of the chamber as a whole.

To restore the refrigerating system to normal operation after defrosting, the valve 60 is closed, thereby shutting off hot gas from the evaporator and the valve 43 is opened to reconnect the suction header 30 to the compressor. The liquid refrigerant stored in the sump 40 may then be returned to the evaporator. In the exemplary system this is done by closing the valve 47 in the sump vent line 46 and opening a valve 61 in a branch of the hot gas line 41 to direct the flow of gas into the sump 40. The pressure of the gas serves to force the liquid refrigerant from the sump through the conduit 45 into the liquid header 27, from which it enters the evaporator by way of the conduit 21, as heretofore described.

When the sump 40 is emptied of liquid refrigerant, the valves 44 and 61 are closed and the valve 42 is opened to admit fresh refrigerant into the system under control of the float valve FV. Operation of the system then proceeds in the normal manner.

The various valves of the refrigerating system may be operated manually in the sequence above described to defrost the evaporator and to restore the system to operating condition. However, to obtain maximum operating efficiency and to reduce the cost of supervision, the invention provides a simple and effective control system by which the defrosting and restarting of the refrigerating system is effected automatically when conditions require such action.

In applying such automatic control to the exemplary refrigerating system, the valves 42, 43, 44, 47, 60 and 61 are provided with individually power operated actuators 42S, 43S, 44S, 47S, 60S and 61S, preferably in the form of solenoids. These valves may be of any suitable construction, such as that shown for the valve 43 in Fig. 3. Thus the valve has a casing 65 with an internal passage and a movable valve member in the form of a disk 66 for opening or closing the passage. The valve member is normally held in closed position by a spring 67 and is moved to open position by its associated actuator or solenoid 43S, in the case of the valve illustrated. For this purpose the valve member is provided with a stem 68 connected with the solenoid plunger 69 so that the solenoid when energized is operative to lift the valve member from its seat and open the valve passage for the flow of gas or liquid therethrough.

While any suitable means may be utilized to initiate a defrosting operation, it is preferred to employ means which becomes operative in response to a condition of the equipment indicating the need for defrosting, as for example, the accumulation of a predetermined amount of frost on the heat exchange surfaces of the evaporator, that is, within the tubes 16. In the exemplary system, advantage is taken of the fact that the resistance to air flow through the tubes 16 increases progressively as the frost coating is built up, thereby causing a corresponding fall in the current requirements of the blower motor M. Accordingly, means is incorporated in the motor circuit for responding to this change in current flow, such means comprising, in this instance, a current relay R1 which becomes energized sufficiently to open normally closed switch contacts R1-1 when the motor current falls to a predetermined value. The opening of the switch con-

tacts R1-1 is utilized to initiate the defrosting operation, as will appear presently.

As shown in Fig. 4 of the drawing, current is supplied to the motor M from a power line comprising the conductors L1, L2 and L3 through switch contacts R2-1, R2-2 and R2-3 of a motor control relay R2. This relay is energized to start the motor by closure of a manually operable starting switch S-1 and is thereafter maintained energized in a holding circuit including the switch contacts R2-2, the normally open contacts R1-1 of the current relay R1, and a normally closed manually operable stop switch S-2.

Connected in parallel with the relay R2 and energized and deenergized simultaneously therewith are a pair of relays R3 and R4. Relay R3 when energized as it is during the normal operation of the refrigerating system closes switch contacts R3-1 and R3-2 to complete energizing circuits for the valve solenoids 42S and 43S. The solenoids when energized open their associated valves 42 and 43, as hereinbefore described, to initiate flow of refrigerant to and from the evaporator. Relay R4 when energized opens normally closed switch contacts R4-1 and R4-2 for purposes to appear presently.

Deenergization of relay R1, which occurs upon the accumulation of a predetermined amount of frost on the evaporator tubes as above explained, opens the holding circuits for the relays R2, R3 and R4 and the relays become deenergized. Relay R2 opens switch contacts R2-1, R2-2 and R2-3 to stop the motor M and thus interrupt the circulation of air through the evaporator. Relay R3 opens switch contacts R3-1 and R3-2 to interrupt the circuits for the solenoids 42S and 43S, which become deenergized and permit their associated valves to close. The compressor-condenser unit is thus shut off from the evaporator and the other elements of the refrigerating system associated with the evaporator.

Relay R4 when deenergized closes switch contacts R4-1 to complete circuits for the valve solenoids 44S, 47S and 60S. The circuit for the solenoid 44S includes normally closed switch contacts R5-1 of a relay R5 and the circuit for the other solenoids includes normally closed switch contacts R6-1 of a relay R6. Relay R4 also closes switch contacts R4-2 to prepare a re-energizing circuit for the motor control relay R2. Energization of the solenoids 44S, 47S and 60S results in the transfer of the liquid refrigerant from the evaporator 6 to the sump 40, as previously described, and hot gas from the compressor-condenser unit is fed into the accumulator to melt the frost accumulated in the tubes 16.

While a timer or the like may be utilized to terminate the defrosting operation if desired, in order to avoid unnecessarily increasing the temperature of the refrigerating chamber 5, it is preferred to employ for that purpose a control device 70 responsive to a temperature increase in a selected part of the refrigerating system. As herein shown, the temperature responsive device 70 comprises a bimetal strip 71 supported closely adjacent or in contact with the horizontal leg 28 of the liquid header 27. Upon complete defrosting of the evaporator 6 the hot gas passes through the inlet conduit 21 to the liquid header and thus raises the temperature of the header.

The bimetal strip 71 responds to the rising temperature of the header by swinging to the right, as viewed in Fig. 4, and at a predetermined

temperature closes switch contacts **12** to complete an energizing circuit for relay **R6**. Relay **R6** becomes energized, opens switch contacts **R6-1** to interrupt the circuits for solenoids **47S** and **60S** and close switch contacts **R6-2** to complete a holding circuit for itself, this latter circuit including contacts **R4-1** of relay **R4**.

Relay **R6** also closes switch contacts **R6-3**, **R6-4** and **R6-5**. Closure of switch contacts **R6-4** completes an energizing circuit for valve solenoid **61S** by way of switch contacts **R5-2** and closure of switch contacts **R6-5** completes an energizing circuit for solenoid **43S**. Accordingly, at this stage of the cycle, valve **42** is closed shutting off the supply of liquid refrigerant. Valve **47** closes to seal the vent for the sump **40** and valve **60** closes to interrupt the flow of hot gas to the evaporator. Valve **43** is opened to reconnect the suction header **30** to the compressor and valve **61** is opened to admit hot gas under pressure to the sump. The liquid refrigerant in the sump is now returned to the evaporator, as explained above.

As the last of the liquid refrigerant is forced out of the sump **40**, a suitable control device, such as a float actuated switch **FS**, installed in or associated with the sump, closes to complete an energizing circuit for relay **R5**, which circuit was previously prepared by closure of switch contacts **R6-3**. Relay **R5** becomes energized and opens switch contacts **R5-1** and **R5-2** to interrupt the circuits for solenoids **44S** and **61S**. These solenoids close their respective valves, thus shutting off the sump **40** from the rest of the refrigerating system. Connected in parallel with relay **R5** and energized simultaneously therewith is a relay **R7** which closes switch contacts **R7-1** to energize valve solenoid **42S** and thus open the refrigerant supply valve **42**. Relay **R7** also closes switch contacts **R7-2** to energize relays **R2**, **R3** and **R4**, the relays locking up through the switch **R2-3** and **R4-1** and performing their functions exactly as in the initial starting of the system. Upon energization of relay **R4**, switch contacts **R4-1** and **R4-2** are opened to interrupt the circuits for relays **R5**, **R6** and **R7** and those relays become deenergized. The control system is thus returned to its normal operating condition and the operation of the refrigerating system proceeds in the usual manner.

It will be apparent from the foregoing that the invention provides a refrigerating system of novel and advantageous construction. Defrosting of the system is greatly facilitated by the novel manner in which the evaporator is positioned and related to the other elements of the system, and freezing of the water resulting from defrosting is effectually prevented by the arrangement for heating the waste system while the defrosting operation is in progress. The evaporator itself is simple in construction and provides a maximum area of heat transfer surface while offering a minimum of resistance to the flow of air thereover.

The invention also provides an improved control system by which defrosting of the evaporator may be effected without the intervention of an attendant and at the precise time that such action is required. The system is thus maintained in efficient operating condition at all times and the cost of supervision is materially reduced. The control system is simple in construction and reliable and foolproof in operation.

I claim as my invention:

1. In a system for maintaining sub-freezing

temperatures in a refrigerating chamber, the combination of partitions forming a compartment adjacent said chamber for connecting therewith through two openings, a refrigerant evaporator comprising a cylindrical shell disposed in one of said openings, headers closing the ends of said shell, and tubes extending longitudinally through said shell and through said headers providing passages for the flow of air from said chamber to said compartment, means for supporting said shell and said tubes in an inclined position, a source of liquid refrigerant, liquid conduit means for supplying liquid refrigerant from said source to said evaporator to cool said tubes below the freezing temperature of water, a blower in said compartment operative to draw air through said tubes into the compartment and to discharge the air through the other of said openings, the air passing through said tubes leaving a deposit of frost on the surfaces of said tubes during normal operation, a source of hot refrigerating gas under pressure, a hot gas conduit between said source of hot gas and said evaporator, means for closing said liquid conduit for discontinuing the supply of liquid refrigerant to said evaporator, means for opening said hot gas conduit for charging the evaporator with hot gas effective to melt the frost from said tubes, the liquid condensate resulting from said melted frost flowing along said tubes and said shell to the lower end of said shell, a condensate conduit positioned under said lower edge to receive said condensate, a gas tight jacket surrounding a portion of said last mentioned conduit, said hot gas conduit being interconnected with said jacket to cause the hot gas to circulate around said condensate conduit before entering said evaporator, said hot gas serving to heat the condensate to prevent its freezing in said condensate conduit.

2. A refrigerating system comprising, in combination, a plurality of evaporators including air conduits defining heat exchange surfaces adapted to absorb heat by converting a refrigerant from a liquid to a gaseous state, a compressor, conduit means connected to said compressor and having individual branches connected to each of said evaporators, a condenser connected to the outlet of said compressor for converting to liquid the hot gas discharge under pressure from said compressor, conduit means connected to said condenser and having branches connected to each of said evaporators for conveying liquid to said evaporators, a refrigerant storage sump, conduit means connected to said sump and having branch lines connected to said evaporators, a hot gas conduit associated with each evaporator and connecting said respective evaporators with the outlet of said compressor, conduit means interconnecting said sump with the outlet of said compressor, blower means associated with each of said evaporators for effecting forced circulation of air through said air conduits, the moisture in said air collecting on said surfaces in the form of frost, control means associated with each of said evaporators and operative in response to the accumulation of a predetermined quantity of frost in said air conduits and the respective evaporators for interrupting the operation of the respective blower means and for initiating the defrosting of said respective evaporators by stopping the flow of fluid from said condenser to said evaporator, opening said evaporator to said sump, and introducing hot gas to said evaporator from

said compressor, second control means associated with each evaporator and responsive to an increase in the temperature of the gas in said evaporator undergoing defrosting operation to automatically stop the defrosting action by cutting off the supply of hot gas to said evaporator, and introducing hot gas from said compressor into said sump to drive liquid refrigerant back into said evaporator, and a third control associated with said sump and responsive to a reduction in the liquid level in said sump to initiate a refrigerating cycle by closing off the supply of hot gas to said sump, closing off said sump from said evaporator, and by connecting said evaporator to the suction side of said compressor and to the liquid supply of said condenser.

3. In a refrigerating system having a source of liquid refrigerant and a source of hot gas under pressure, the combination of a refrigerant evaporator, a temporary liquid storage sump, conduit means connecting said sources with said evaporator and said evaporator with said sump, and valves in said conduit means normally set to admit liquid refrigerant to said evaporator and to prevent the flow of hot gas thereto and to prevent the flow of liquid from said evaporator to said sump, first control means operative in response to the accumulation of frost on said evaporator for operating a selection of said valves to interrupt the supply of liquid refrigerant to said evaporator, to open said conduit between said evaporator and said sump, and to admit hot gas to said evaporator to drive the liquid from said evaporator into said sump and to defrost said evaporator, conduit means connecting said source of hot gas to said sump, a normally closed

5
10
15

valve in said last mentioned conduit means, second control means having a temperature sensitive element in thermal contact with the gas in said evaporator and operative in response to an increase in temperature of the gas in said evaporator beyond a predetermined point for operating a selection of said valves to interrupt the flow of hot gas to said evaporator and to introduce hot gas into said sump to force the liquid therein back into said evaporator, and third control means in contact with the liquid in said sump and responsive to lowering of the liquid level in said sump for operating said valves to interrupt the supply of hot gas to said sump, to close said conduit between said evaporator and said sump and to re-admit liquid from said source of liquid refrigerant to said evaporator to restore the refrigerating system to its original condition.
